UNITED STATES PATENT OFFICE.

ARTHUR BARLOW, OF BROOKLYN, NEW YORK, ASSIGNOR OF ONE-HALF TO WALTER McDougall, OF BROOKLYN, NEW YORK.

SUPPORTING DEVICE FOR NURSING-BOTTLES.

1,271,994.

Specification of Letters Patent.

Patented July 9, 1918.

Application filed November 25, 1913. Serial No. 802,957.

To all whom it may concern:

Be it known that I, ARTHUR BARLOW, a citizen of the United States, and a resident of New York, borough of Brooklyn, in the county of Kings and State of New York, have made and invented certain new and useful Improvements in Supporting Devices for Nursing-Bottles, of which the following is a specification.

10 My invention relates to a supporting device for nursing bottles, the object of the same being to provide an article of this kind or character which shall be simple and economical to manufacture, and which may therefore be sold at a comparatively low cost, which may be easily and readily attached to or detached from a chair, crib, or other article of furniture or support, and which may be instantly turned or adjusted to 15 bring the bottle within or taken out of reach of the infant. With these and other ends in view, the invention consists in certain novel features of construction and combinations of parts as will be hereafter fully 20 described and pointed out in the claims.

In the accompanying drawings, Figure 1 is a view in perspective of a bottle supporting device constructed in accordance with my improvement.

30 Fig. 2 is a sectional view through the clamping device and taken on the line 2—2 of Fig. 3.

Fig. 3 is a sectional view taken through the clamping device on the line 3—3 of 35 Fig. 2.

Fig. 4 is a detached perspective view of the clamping plate.

Fig. 5 is a sectional view taken through the bottle clamping end of the support, the 40 bottle being removed therefrom.

By reference to the drawings it will be seen that the supporting device consists of a main rod or bracket 6, twisted or bent in several directions, as illustrated at 7, and 45 into one end of which telescopes an auxiliary arm 8, the latter being slotted or slotted as illustrated at 9 in order to impart thereto a spring tension for holding said arm 8 in any desired adjustment with relation to the main arm 6. On the outer end of this auxiliary arm 8 is formed, or has secured thereto, a bottle clamp 10, preferably made of spring metal and shaped to 50 partially encircle the bottle 11, this construction and arrangement of parts permit-

ting the auxiliary arm 8 to be partially pulled out of the main arm 6 to thereby slightly lengthen the same, and also to permit of its being twisted or turned within said main arm 6 in order to allow of the 60 bottle 11 being turned in either direction, that is, toward the right or the left, and either toward or away from the infant.

The opposite end of the main arm 6 is detachably secured to the arm 12 of the 65 chair, crib, carriage, or other support, by means of a clamp, this clamp comprising a frame or yoke formed with the two arms 13, the free ends of which are provided with holes or openings through which the main 70 arm 6 passes. Between the arm 12 of the chair or other support and the main arm 6 of the bracket, is located a clamping plate 14, illustrated in perspective in Fig. 4, this clamping plate being slightly bent or curved 75 to conform to the curvature of, and more accurately fit and bear on, the main arm 6 with which it contacts as clearly illustrated in Fig. 3, the edges of this plate being bent downwardly and serrated as illustrated at 15 in order to bite into the wood 80 of the arm 12 and thereby more securely hold the device thereto. To the yoke of the clamp is secured a sleeve 16 internally threaded and through which passes the 85 clamping screw 17, the free end of this screw impinging against the arm 12 of the chair or other support, as illustrated in Figs. 1, 2, and 3, it being readily understood that when the clamping screw 17 is turned it 90 will bear tightly against the arm 12, which in turn bears tightly against the clamping plate 14, and which in turn bears tightly against the main arm 6 passing through the openings in the free ends of the yoke. Furthermore, it will be understood that by loosening the clamping screw 17 the main arm 6 may be moved lengthwise through the ends 95 of the yoke to any desired adjustment, and the main arm 6 turned on its axis, with the 100 result of tilting the bottle into any position as may be desired, at the same time permitting the clamp, with its engaging arm 6, to be moved along into any position on the arm 12. In other words, by constructing 105 and arranging the clamp as illustrated and above described, and also by the employment of the telescoping auxiliary arm 8, the bottle holding clamp 10 may be brought into any desired position with relation to 110

2
the arm of the chair or other support as
may be desired, that is, it may be moved to-
ward or away from the arm of the chair,
and it may be raised or lowered and tilted
5 by turning the main arm 6 on its axis, and
the auxiliary arm within the main arm,
and thereby permitting the bottle to be
moved to any place or location with regard
to the chair, crib, etc., and into any desired
10 position.

It will also be understood from the fore-
going that the invention is exceedingly sim-
ple and economical in construction, and
when nickel plated or otherwise ornamented,
15 presents a very neat and pleasing appear-
ance, and that the contained bottle may be
easily and readily adjusted to any location
and position by simply loosening the clamp-
ing screw 17 and turning the auxiliary arm
20 8 held by friction or spring tension in the
very end of the main arm 6.

What I claim is:

1. A bottle supporting device of the char-
acter described comprising a bent main arm,
25 and a telescopic auxiliary bottle clamping
arm fitting in one end thereof, and a clamp,
said clamp comprising a yoke, through the
free ends of which passes said main arm, a
clamping plate located and movable between
30 the arms of said yoke, and a clamping
screw passing through said yoke whereby
to hold the several parts in their proper rela-
tive positions.

2. A bottle supporting device of the char-
acter described and consisting of a main arm
35 having fitted in one end thereof an adjust-
able auxiliary bottle clamping arm, and a
clamping device, the latter comprising a
yoke the free ends of which are provided
40 with openings through which said main arm
passes, a curved clamping plate located be-
tween the arms of said yoke and impinging
against said main arm and having the bent
edges thereof serrated for the purpose of
45 securely holding the same in position on a
chair or other support, and a clamping
screw passing through said yoke and adapt-
ed to bear at its free end against the said
chair or other support, substantially as de-
50 scribed.

3. A bottle supporting device of the char-
acter described comprising a main arm, an
auxiliary bottle clamp rotatably carried at
one end thereof, and a clamp, said clamp

comprising a yoke, through the free ends of 55
which passes said main arm, a clamping
plate located and movable between the arms
of said yoke, and a clamping screw passing
through said yoke whereby to hold the sev-
eral parts in their proper relative positions. 60

4. A bottle supporting device of the char-
acter described, consisting of a main arm, an
auxiliary bottle clamping arm rotatably car-
ried at one end thereof, and a clamping de-
vice, said clamping device including a yoke, 65
the free ends of which are provided with
openings through which said main arm
passes; a curved clamping plate located be-
tween the arms of said yoke and impinging
against said main arm and having the bent 70
edges thereof serrated for the purpose of se-
curely holding the same in position on a
chair or other support, and a clamping screw
passing through said yoke and adapted to
bear at its free end against the said chair or 75
other support.

5. A clamp for a bottle supporting device
comprising a yoke, the free ends of which
are provided with openings for the passage
of a rod therethrough, a curved clamping 80
plate located between the arms of said yoke
and adapted to impinge against said rod and
having the bent edges thereof serrated for
the purpose of securely holding the same in
position on a chair or other support, and a 85
clamping screw passing through said yoke
and adapted to bear at its free end against
the said chair or other support.

6. A device of the character described
comprising a main arm the upper portion of 90
which is bent and extends at an angle, and
the free end of which bent portion is hol-
low; means for securing said main arm to
a supporting structure; an auxiliary arm ex-
tending into the hollow free end of said 95
bent portion, and which auxiliary arm is ro-
tatably and angularly adjustable within said
free end; and clamping spring fingers car-
ried by said auxiliary arm.

Signed at New York city, borough of 100
Brooklyn, in the county of Kings and State
of New York, this 19th day of November,
A. D. 1913.

ARTHUR BARLOW.
